UNITED STATES PATENT OFFICE.

LYMAN SMITH, OF KANSAS CITY, MISSOURI.

APPARATUS FOR TRANSFERRING GRAIN AND THE STORAGE THEREOF.

SPECIFICATION forming part of Letters Patent No. 321,769, dated July 7, 1885.

Application filed February 26, 1885. (No model.)

To all whom it may concern:

Be it known that I, LYMAN SMITH, of Kansas City, in the county of Jackson and State of Missouri, have invented certain new and useful Improvements in Apparatus for Transferring Grain and Storage thereof; and I do hereby declare that the following is a full, clear, and exact description of the invention, which will enable others skilled in the art to which it appertains to make and use the same, reference being had to the accompanying drawings, and to the letters of reference marked thereon, which form a part of this specification.

My invention relates to combined hydraulic and pneumatic apparatus for transferring grain, coal, sand, and other similar substances from one place of storage to another, and is designed to be applied in places where it is possible to utilize a head of water for creating an artificial exhaustion of the air for that purpose. My pneumatic grain-conveyers, in which the transfer of grain and like substances is effected automatically by suitable apparatus operated by the exhaustion of the air, are well known in practice, and are fully described in several patents issued to me, and particularly referred to in Patent No. 279,034.

The present improvement consists, essentially, in combining with the said apparatus, or in substituting for the air-pump in the said apparatus, a water-reservoir in which the water is raised and lowered to perform the function of a piston, as now applied to air-engines, which water is supplied from a suitable source.

Strictly speaking, my invention consists of an improved automatic pumping or exhausting apparatus which may be applied to any use of which such apparatus is capable; but my claims in this application will cover a method of automatic pumping, the claims for the construction being reserved for a future application.

The form of apparatus which I have shown is especially adapted to use in connection with my grain-conveyer; but it should be understood that I do not desire to limit it to that use alone.

In order to enable others skilled in the art to which it appertains to make and use my invention, I will now proceed to describe it in

connection with the accompanying drawings, in which—

Figure 1 is an elevation of my combined hydraulic and pneumatic grain-transfer apparatus, showing partly in section my grain-bin provided with drying devices; and Fig. 2 is an elevation, partly sectional, of my improved automatic pumping or exhausting apparatus.

Similar letters of reference indicate the same parts in all the drawings.

Referring to Fig. 1, A is a vacuum-chamber in the upper part of an elevator, into which chamber the grain or other substance is drawn through the elevator pipe or tube a. B is the pipe to which the pumping apparatus is attached for exhausting the air from the chamber A. The pipes or tubes C C' are delivery-pipes, through which the grain falls by gravity to the place to which it is desired to transfer it. All the pipes are provided with suitable supply and cut-off valves, whereby an automatic operation of the grain-conveyer is secured.

The construction and operation of this part of my invention have been fully described in other applications of mine and need no special description here.

My improved pumping apparatus is connected by a pipe, B', to the pipe B, and I may connect to the same pipe B several pumps, as shown in Fig. 1, and the said pipe may branch off to the vacuum-chambers of several different elevators or to several vacuum-chambers in the same elevator. Each pump is also connected by a pipe, D', to a water-supply pipe, D, and consists, essentially, of the following parts:

A chamber or reservoir, E, of suitable dimensions, is preferably supported in masonry along the bank of a river or elsewhere near the water. An outlet-pipe, E', leads from the bottom of this chamber or reservoir, and terminates, preferably, under the surface of the river. It may terminate in the open air, in which case it is not necessary that the reservoir E should be supported near a body of water.

The inlet-pipe D' and the outlet-pipe E' are provided, respectively, with the valves d and e. These valves are operated by the compound gravity-lever F in such a manner that

when the lever is in a position to open one valve the other will be closed.

The compound lever consists of the vertical rod F and the weighted arms f f, attached to the valves. The outer ends of the arms f f are joined to the rod F by an elongated slot and a pin attachment. Secured to the rod F, as shown, is a cylindrical receptacle or cylinder, F', capable of holding water, and provided with an outlet-pipe, g, by which the water may be drawn off, and a stop-cock, g', by which to regulate the rapidity with which it shall be emptied. A small pipe, G, leads from the pipe E', and, after running up to a height level with the top of the chamber, bends down and terminates directly above the cylinder F'. The pipe G is closed by the valve h, and the pipe B by the valve c. A fourth pipe, I, communicating with the open air, leads from the top of the reservoir E and is closed by the valve i.

The operation of my pumping apparatus is as follows: It being understood that the weights on the arms f f are such that they operate the lever to open the valve d and close the valve e, and it being further understood that the cylinder F' is made large enough, so that the weight of water therein when it is full is more than enough to overbalance the weights on the arms f f, and so to reverse the positions of the valves, the water, being let in through the pipe D, passes into the reservoir E, and gradually fills first the pipe E', and then the pipe G and the reservoir, the valve e preventing the exit of the water from the pipe E', and the valve h allowing its entrance into the pipe G. As the water rises the air is expelled from the reservoir through the pipe I, and the valve c of the pipe B is pushed against its seat. When the reservoir is nearly or quite filled, the water in the pipe G begins to overflow and fall into the cylinder F', and after a little time the weight of water in the cylinder F' overcomes that of the weighted arms f f and turns the valves d and e, so that the supply is cut off and the exit open through the pipe E under the surface of the water. The cock g' in the tube g is turned so as to allow a gentle flow of water out of the cylinder F'. The amount of outflow as compared with the amount of inflow through G is graduated by experiment so that the cylinder will be filled and afterward emptied in a convenient time or in the time required for properly operating the pump. As soon as, or perhaps before, the water is emptied from the cylinder F', the weights will restore the valves, and the same operation will be repeated. It is intended that this restoration of the valves shall take place before the water has all been exhausted from the pipe E'. During the exhaustion of the chamber or reservoir E the valve i will be closed and the valve e opened. It is evident, therefore, that by the successive movements of the water in the reservoir the pipe B will be acted upon by suction, and that

in the apparatus shown in Fig. 1 the air will be exhausted automatically from the chamber A. It is also evident that the pipe I will be alternately closed by suction and opened by 70 pneumatic pressure. The pipe I may, if desired, be connected to any suitable motor, so as to utilize this pressure. The water in the reservoir acts, it will be observed, in the place of an ordinary piston, and the water behind 75 that in the reservoir serves the function ordinarily performed by the piston-rod.

The object of placing the end of the pipe E' under water is so that no air may enter through the pipe into the reservoir. 80

Any other means besides those shown for cutting off the water-supply and providing an exit may be employed without a substantial departure from the broad principles of my invention. 85

As referred to in the patent above cited, this system is designed to preserve grain from moisture, and for drying and curing it, and for destroying the animalecule and grain insect, and applies particularly to grain that becomes wet in transit or from other cause. This feature is a long-felt want in handling grain, and is calculated to save untold millions of bushels, as well as to restore it to its natural condition and money value. 90

It is well known that grain when wet is regarded as damaged, and is sold for little more than half its value when dry, really when the said grain is otherwise in a sound condition. By my process I can in a very short space of 100 time revivify and dry this wet grain, and restore it to its original freshness and purity, just as much so as when standing in the ear when it got wet and was immediately dried by the blowing of the wind. My process is 105 just as natural, and while I use artificial means for drying, the same as nature did in the field, I use pure atmospheric air, the said air surrounding every grain and permeating the entire mass. 110

Any of my bins may be made applicable to the drying process of grain; but I prefer to make them of a conical shape at both ends when applied to grain, for the reason that when the bin is exposed to the weather the 115 cone-shaped top sheds the rain or snow, and by having the bottom cone-shaped the grain or other granular substances will slide to the extreme outlet by its own gravity.

While this drying process is very beneficial 120 for grain generally, it cannot be surpassed for seed-grain.

It is well known to farmers and to persons generally handling seed-grain that a large percentage of it is attacked by insects—such as 125 worms, weevil, and the like—which unsuits it for seed. Those insects get into the germ of the grain unbeknown to the farmer or merchant handling the grain, which destroys it for seed purposes, so that when grain of this 130 character is sown it fails to come up, and at a time too late to plant other grain. Thus a

large percentage of that year's crop is lost. Now, with my invention the said grain can be first dried; then all the air is exhausted from the bin, in which a vacuum is created. The 5 grain may be left in this vacuum for a certain length of time, when, in the absence of atmospheric air, every atom of animal life is destroyed. It will be fully understood that only atmospheric air is used in my drying process, 10 and therefore the grain is not subjected to heated or vitiated air.

Having now described my invention, what I claim, and desire to secure by Letters Patent, is—

15 1. The method of pumping automatically, which consists in alternately introducing water into a reservoir connected with a suction-pipe, and cutting off the supply of water and affording an outlet therefor by means of the 20 overflow, substantially as set forth.

2. The method of pumping automatically, which consists in alternately filling with water a reservoir connected with a suction-pipe and emptying the same to create a vacuum, sub- 25 stantially as set forth.

3. The process of utilizing water in a reservoir to produce a vacuum-power and an air-compressor alternately, substantially as described.

30 4. The process of utilizing a water-reservoir as a motive power for conveying grain and the like, which consists, first, in displacing the wa-

ter in the reservoir, thereby creating a vacuum, then applying the suction-power of said vacuum to an air-tight chamber, which in turn 35 is connected to a place in which grain is stored, in such manner that the grain rushes with the air to the vacuum-chamber, substantially as described.

5. The process of utilizing the water in an 40 air-tight reservoir, which consists in automatically raising the water in the reservoir, by which the air is displaced and compressed into a smaller compass, then connecting the compressed-air chamber to a place where grain is 45 stored in such manner as to force the grain out of said chamber by the force of said compressed air, substantially as described.

6. The process herein described of drying and curing grain, which consists of first drawing air through it in an air-tight bin or receiver 50 until it is dry, then exhausting said bin or receiver of the air therein contained, then permitting it to remain in the storage-places sufficiently long to kill or destroy the life of the insect in or among the grain, as set forth. 55

In testimony that I claim the foregoing as my own I affix my signature in presence of two witnesses.

LYMAN SMITH.
